ENGINE CYLINDER STRUCTURE

Anker K. Antonsen, Beloit, Wis., assignor to Fairbanks, Morse & Co., Chicago, Ill., a corporation of Illinois

Application July 8, 1952, Serial No. 297,677

10 Claims. (Cl. 123—193)

This invention relates to improvements in cylinder structures for internal combustion engines, and more particularly to an improved cylinder structure of sectional character, for engines of the opposed piston type.

In high compression engines such as diesel engines, the weight factor generally is quite large, due in part to heavy sectioned cylinders heretofore necessary to accommodate the high compression and working pressures. However, as a result of improvements in materials, as high strength alloy steels and the like, it is now feasible to construct relatively light-weight, adequate strength cylinders for engines of the type indicated. The present invention is concerned with such light-weight cylinders, and especially cylinders for opposed piston engines, wherein the over-all length of the cylinder liner is appreciable.

It is a principal object of the present invention to provide a light-weight, relatively thin-walled cylinder liner for opposed piston engines, wherein, in order to facilitate its manufacture, the liner is formed or comprised of a plurality of liner sections secured together in end-to-end relation, with the liner constructed such that the center section provides the combustion chamber of the cylinder, while one end section contains exhaust ports, and the other or opposite end section contains air admission ports.

Another principal object of the invention is to provide a sectional cylinder liner of the character indicated, adapted for assembly support in the engine frame such that the liner over the major portion of its length, is free to undergo expansion and contraction displacement relative to the frame.

Another object is to effect improved cooling of the liner, particularly the center or combustion chamber section thereof, by constructing the liner to have cooling fluid jacket provisions and including fluid passage means in the central zone of the center section of the liner.

Other important objects and advantages of the present invention will appear from the following description of a presently preferred embodiment thereof, as illustrated in the accompanying drawings, wherein:

Fig. 1 illustrates in longitudinal sectional elevation, a cylinder structure embodying the improvements of the present invention, the view including fragmentary parts of the engine frame in supporting relation to the cylinder.

Fig. 2 is a transverse section of the cylinder structure as viewed from line 2—2 in Fig. 1.

Fig. 3 is another sectional view in transverse section, as taken along line 3—3 in Fig. 1.

Fig. 4 is a view in longitudinal elevation, of the center section of the presently improved liner structure.

With reference to the drawings, the presently improved cylinder structure is shown in Fig. 1 as including a cylinder liner comprised of a center section 10 and opposite end sections 11 and 12. The several sections are of light-weight construction, being formed of a suitable high-strength alloy steel permitting relatively thin-wall formation of the liner sections, yet providing the requisite strength to accommodate high-compression and working pressures. For opposed piston application, the end section 11 of the liner is provided with a plurality of air admission ports 14 preferably extending in a belt about the inner end portion 15 of the section, while the opposite end section 12 is provided with a plurality of exhaust ports 16 about the inner end portion 18 and arranged as more particularly illustrated in Fig. 3. In assembly of the liner sections, the inner end margin 19

2

of section 11 is internally recessed to receive, as by a lap-fit therein, the adjacent end 20 of center liner section 10. The liner ends 19 and 20 thus lap-engaged, are rigidly secured together preferably by welding or hydrogen brazing in well-known manner. Similarly, the inner end margin 22 of liner section 12, is internally recessed for lap-fit reception of the adjacent end 23 of the center liner section 10. These ends also are rigidly connected, as by welding or brazing.

10 The center section 10 providing the combustion chamber zone of the liner, is formed in its central area, to provide a relatively thickened wall portion 24. In the external surface of wall portion 24 are formed a first series of channels 26 (Fig. 4) arranged about the liner section and directed longitudinally toward the end 20 of the sections, and a second series of channels 27 about the section and directed longitudinally toward the opposite end 23 of the section. The adjacent ends of the channels in the two series, are separated by an annular land portion 28. The wall portion 24 further, is thickened internally of the section substantially in the center region of wall 24, to provide an internal annular boss or projection 30 substantially midway between the ends of the center section 10. Formed in the projection 30 are a plurality of passages 31 each being of figure "8" form in sectional view as shown in Fig. 1. These passages may be formed by suitable drilling operations, as will be appreciated. Each thereof is open at 32 to one of the channels 26 in the first series, and open as at 34 preferably to a corresponding one of the channels 27 in the second series. Surrounding the center section 10 is a cylindrical cooling fluid jacket member 35 providing an internal cylindrical surface 36 closely embracing the thickened portion 24 of the liner, as in over-lying relation to the channels 26 and 27, and with a portion of the jacket member in surface seating on the land 28 and cooperating therewith to complete separation of the channels in such zone. Consequently, the passages 31 afford interconnection of the two series of channels for flow of cooling fluid therebetween, and in addition, serve to conduct cooling fluid into effective cooling relation to the projection 30 in the liner combustion zone.

As shown in Fig. 1, the liner section 12 is formed to provide a cylindrical wall portion or extension 38 in integral connection with the inner end portion 18, disposed in surrounding relation to the adjacent portion of the center liner section 10 and radially spaced therefrom. The free end 39 of extension 38 is in fluid-sealed, telescopic engagement with the end 40 of jacket member 35 such as to permit limited relative longitudinal displacements of these parts, the seal being effected in any suitable manner, as by an annular seal ring 42. The opposite end portion 43 of jacket member 35 embraces the inner end portion 15 of liner section 11, preferably in sleeved relation thereto, and is connected to the liner section as by one or more dowel pins 44 and a snap-ring 46. Moreover, the jacket engagement with the liner section 11 is fluid-sealed as by the seal ring 47, to prevent fluid leakage from the jacket chamber 48. Since the end 43 of jacket member 35 overlies the air ports 14, such end of the jacket member is formed with port-openings 49 each in direct communication with one of the ports 14 so that scavenging and combustion air may be delivered to and through the latter ports.

65 The center liner section 10 in the zone of its internal projection 30, is provided with one or more openings, as for example the four openings 50, 51, 52, and 53, shown in Fig. 2, to accommodate fuel injection means and other devices. Aligned with these openings are openings 54 in the jacket member 35. As shown, suitable fuel injection valve devices 55 are received in openings 50 and 51, while a starting air control valve 56 is received in opening 52, and a plug 57 in opening 53. The plugged opening 53 may be utilized for mounting an indicator device such as a pyrometer or the like (not shown).

80 The cylinder structure of the character now described, is mounted in the engine in an improved manner such as to allow full freedom of the liner to undergo longitudinal expansion and contraction displacements with respect to the engine frame. The frame shown only in

fragmentary part, includes upper crankcase wall 60 terminating in an upper frame deck plate 61 having central circular opening 62 slidably receiving therein, the flanged head end 64 of jacket member 35, the latter carrying a suitable seal ring 65 in engagement with the marginal wall of the deck plate opening 62. An intermediate frame deck plate 66 has a central opening 68 slidably receiving the jacket member 35 in the portion thereof adjacently below the air port openings 49, in fluid-sealed relation therein as through the seal ring 69. A further intermediate frame deck plate 70 has a central opening 72 slidably receiving the lower end portion 40 of jacket member 35, while a lower deck plate 73 provided as a part of lower crankcase wall 74, is formed with a central opening 76 freely receiving therethrough, the lower end portion of liner section 12. Embracing the liner section 12 and a part of its wall extension 38, is a fluid-jacketed exhaust belt member 77 which is supported on the lower deck plate 73, as shown. The liner section 12 is free in the exhaust belt member for longitudinal expansion and contraction displacement therein, there being a suitable degree of clearance provided at 78 between liner shoulder 30 and the shoulder receiving recess 81 in member 77, to accommodate the maximum of such displacements. As shown by Fig. 1 and in section by Fig. 3, the liner exhaust ports 16 open into chambers 82 of the belt member 77 for ultimate discharge of exhaust gases through exhaust manifolds 84 (shown in part).

Externally on the liner section 11 inwardly adjacent its outer end, is an annular shoulder 83 against which is received a flanged mounting ring 86. The ring is fixed to the liner section on said shoulder, as by the snap-ring 88, and has its flange portion 89 in cylinder liner supporting engagement (through a suitable resilient gasket 90) with a cylinder mounting deck plate 92 carried by the upper crankcase wall 60. Bolts 93 serve to effect firm securing of the flange 89 to plate 92.

Thus it will appear from the foregoing, that the sectionally formed cylinder liner structure is fixedly secured to the engine frame in only one zone of the liner, as at a point near the end of the liner section 11. In an engine having its cylinders vertical, such zone of liner securing to the frame will be at the top, so that the liner will be in suspension therefrom. In any case, it is to be observed that the liner structure throughout its length from the point of its securing to the frame, to the end of liner section 12, is supported by the several frame deck plates and the exhaust belt member 77 against lateral displacement, with the liner free in these frame parts to undergo longitudinal expansion and contraction displacements. The liner structure capable of such compensating displacements, includes the jacket member 35 and the liner wall extension 38 which together with the liner sections, form a jacketed cylinder liner unit. Moreover, by reason of the relative telescopic engagement of the liner wall extension 38 and the adjacent end of the jacket member 35, and the securing of the member 35 at its opposite end to the liner section 11 near the zone of liner securing to the frame plate 92, the connected liner sections 10 and 12 together with the inner end portion 15 of liner section 11, are free to undergo expansion and contraction displacements relative to the jacket member 35.

As illustrated in Fig. 1, cooling fluid such as water, is delivered to the jacket space 100 of the exhaust belt member 77 through one or more delivery conduits 101. The fluid circulates in the space 100 and thence passes by way of a suitable connection (not shown), to the liner jacket space 102. From there it flows through channels 27, into and through passages 31 in liner projection 30, to the channels 26 and thence into jacket space 48. Discharge from the latter space may be by way of discharge conduit 104.

It is clear from the sectional view of Fig. 1, that the sectional cylinder structure including the jacket member 35, may be readily bodily displaced as a unit, into assembly position in the frame through the relatively large-diameter central opening 105 in the mounting plate 92. Conversely, the cylinder unit may be equally readily removed through the same opening 105.

Having now described and illustrated a presently preferred embodiment of the invention, what is claimed is:

1. A cylinder structure for an internal combustion engine, comprising an engine frame, a cylinder liner comprised of separate liner sections in integrally joined end

connection one to another, supported by the frame against lateral displacement, and securing means between the engine frame and the outer end portion of a liner section at one end of the liner, for retaining the liner in the frame, said liner in the major longitudinal extent thereof from said securing means, being free in the frame for longitudinal expansion and contraction displacements.

2. A cylinder structure for an internal combustion engine, comprising an engine frame, a cylinder liner comprised of at least three separate, relatively thin-wall liner sections in integrally joined end connection one to another, said liner being supported by the frame against lateral displacement, and mounting means between the engine frame and one end section of the liner near the outer end of the latter, for retaining the liner in the frame, the remainder of the liner being free in the frame for longitudinal expansion and contraction displacement.

3. A cylinder structure for an internal combustion engine, comprising an engine frame, a cylinder liner comprised of separate center and end liner sections in end connection one to another, a jacket member sleeved on the liner, said liner and member being supported by the frame against lateral displacement, mounting means between the engine frame and one end liner section near the outer end of the latter, for retaining the liner in the frame, and means securing said jacket member solely at one end thereof to said liner, the liner over the length thereof from said mounting means, being free relative to the frame, for longitudinal expansion and contraction displacements.

4. A cylinder structure as defined by claim 3, wherein the said jacket member securing means is provided between the said one end of the jacket member and the said one end liner section, such that the liner over the major length thereof from the said securing means is free in respect to the said jacket member, for lengthwise expansion and contraction displacements relative to the member.

5. A cylinder structure for an internal combustion engine, comprising a cylinder liner constituted by separate, relatively thin-wall liner sections in integrally joined end connection one to another, an end section having a wall extension in relatively spaced, surrounding relation to a portion of the adjacent liner section, said adjacent liner section having external channels arranged about the central portion of the section, and a cooling fluid jacket member about said adjacent liner section and the channels thereof, extending in fluid-sealed, lapped relation to the free end of said wall extension.

6. A cylinder structure for an internal combustion engine, comprising a cylinder liner constituted by separate, relatively thin-wall liner sections in integrally joined end connection one to another, an end section having a wall extension in relatively spaced, surrounding relation to a portion of the adjacent liner section, said adjacent liner section providing an internal annular projection intermediate its ends and having external channels arranged about the central portion of the section, said projection having passage means therein opening to said channels, and a cooling fluid jacket member sleeved on the liner with a portion thereof about said adjacent liner section in closely overlying relation to said channels, said jacket member having one end in fluid-sealed, lapped relation to the free end of said wall extension.

7. A cylinder structure for an internal combustion engine of opposed piston type, comprising a cylinder liner constituted by separate, relatively thin-wall liner sections in integrally joined end connection one to another, one end section having exhaust ports and providing a wall extension in relatively spaced, surrounding relation to a portion of the adjacent center section, the opposite end liner section having air admission ports, said center section of the liner providing external channels arranged about the central portion thereof, and a cooling fluid jacket member sleeved on the liner and secured solely at one end thereof to said opposite end liner section, the jacket member overlying the central liner section and the channels thereof, and having its opposite end in fluid-sealed, lapped relation to the free end of said wall extension.

8. A cylinder structure as defined by claim 7, wherein the said center section of the liner is characterized further, by an internal annular projection centrally in the section, and passage means in the projection and opening to the said external channels.

9. A cylinder structure for an internal combustion engine of opposed piston type, comprising a cylinder liner constituted by separate center and end liner sections integrally joined end connection one to another, one end section having exhaust ports and the other end section having air admission ports; said center section being formed in its central region, to provide an annular, internally projecting portion, a first series of channels externally of the section about its central region and extending toward one end of the section, a second series of channels externally of the section about its central region and extending toward the other end of the section, a land portion externally about the center section and separating the first and second series of channels, and passage means in said internally projecting portion, interconnecting the channels of the first and second series; and a cooling fluid jacket member about the center liner section and the channels thereof, and extending to fluid-sealed engagement with said end liner sections.

10. A cylinder structure for an internal combustion engine of opposed piston type, comprising an engine frame, a sectional relatively thin-walled liner assembly comprised of a central liner section, end liner sections one at each end of the central liner section and integrally joined to

the latter, one end liner section having air admission ports and the other end liner section having exhaust ports, the liner assembly being supported by the frame against lateral displacement relative to the frame, and mounting means for the liner assembly provided solely between said frame and the outer end portion of said one end liner section having air admission ports, such that the liner assembly over the major portion of its length extending from said mounting means, is free in the frame for longitudinal expansion and contraction displacements.
